Patented May 22, 1962

192,845

SIZE INDICATOR FOR A GARMENT HANGER

Maurice Cohen, 3580 NW. 52nd St., Miami, Fla.

Filed May 29, 1961, Ser. No. 65,390

Term of patent 14 years

(Cl. D1—3)

FIG. 1

FIG. 2

FIG. 5

FIG. 3

FIG. 6

FIG. 4

FIG. 1 is a perspective view of a size indicator for a garment hanger showing my new design;

FIG. 2 is a side elevational view thereof;

FIG. 3 is a top plan view thereof;

FIG. 4 is a bottom plan view thereof;

FIG. 5 is a front elevational view thereof; and

FIG. 6 is a rear elevational view thereof.

The broken-line representation of numerals and the fragmentary representation of a garment hanger are for purposes of illustration only.

I claim:

The ornamental design for a size indicator for a garment hanger, substantially as shown and described.
